UNITED STATES PATENT OFFICE.

LEO F. ADT, OF TROY, NEW YORK.

DESIGN FOR A COLLAR.

SPECIFICATION forming part of Design No. 32,844, dated June 12, 1900.

Application filed April 12, 1900. Serial No. 12,637. Term of patent 7 years.

To all whom it may concern:

Be it known that I, LEO F. ADT, a citizen of the United States, residing at Troy, in the county of Rensselaer and State of New York, 5 have invented and produced a new and original Design for Collars; and I do hereby declare the following to be a full, clear, and exact description of the same, reference being had to the accompanying drawings, forming 10 a part thereof.

Figure 1 is a perspective view of a collar, showing my new design as arranged when in use. Fig. 2 is a perspective view of the same, showing the ends of the collar separated.

15 As shown in the drawings, the leading or material feature of my design consists of the triangular or wing-shaped projections *b*, extending outward on inclined lines from a col-

lar-band *B*, with the end *A'* of the collar-band *A* extending beyond one of such wing-shaped 20 projections, so that when the ends of the collar are brought into the position indicated in Fig. 1 a V-shaped portion of the end *A'* of the collar-band is exposed between such wing-shaped projections *b*. 25

What I claim as new, and desire to secure by Letters Patent, is—

The design for a collar, as herein shown and described.

In testimony whereof I affix my signature 30 in presence of two witnesses.

LEO F. ADT.

Witnesses:

ROBERT W. HARDIE,
GEORGE B. YOUNG.
